SAFETY DEVICE FOR INTERNAL COMBUSTION ENGINES

Mortimer S. Parkhill, Corning, N. Y., assignor
to Ingersoll-Rand Company, Jersey City,
N. J., a corporation of New Jersey

Application January 9, 1930. Serial No. 419,705

1 Claim. (Cl. 264—16)

This invention relates to internal combustion engines, but more particularly to a safety device for engines of this type in which the fuel charge is electrically ignited.

5 One object of the invention is to prevent the operation of the engine at excessive speeds.

Other objects will be in part obvious and in part pointed out hereinafter.

In the accompanying drawing illustrating one form of the invention and in which similar reference characters refer to similar parts,

Figure 1 is a side elevation of an internal combustion engine and its ignition system having the invention applied thereto.

15 Figure 2 is a transverse view taken through Figure 1 on the line 2—2 looking in the direction indicated by the arrows, and

Figures 3 and 4 are sectional elevations taken 20 through Figure 2 on the lines 3—3 and 4—4 looking in the directions indicated by the arrows.

Referring more particularly to the drawing, A designates an internal combustion engine which may be suitably supported by a base B as may also be an electrical current generating device, 25 such as a magneto C.

The magneto C may be actuated in any suitable and convenient manner, as for instance, by a shaft D which is shown extending longitudinally of the engine A and which may be operatively connected to the crank shaft (not shown) of the engine for imparting rotary movement to the shaft D. The magneto C is shown supporting a distributor E from which lead cables F to spark plugs G in the head H of the engine A.

35 In accordance with the present invention means are provided for bringing the engine to a standstill whenever its speed exceeds that which it may be considered desirable to maintain. To this end the engine is provided with a safety device designated generally by J and which device is adapted to be associated with the shaft D in such a manner that it will be responsive to any acceleration of the shaft D above what may be determined as its normal speed.

45 The safety device comprises a contact K which is suitably secured to the base B of the engine and is connected to the ground terminal L of the magneto C by means of a cable O. The contact K may be suitably insulated from the base B by means of an insulator P which is arranged in a hole Q in the base B and through which hole the contact K extends.

50 Preferably the contact K is disposed closely adjacent the shaft D on which is arranged a bearing designated generally by R and comprising

ing a pair of plates S and T. The plate S is provided with a hub U which encircles the shaft D and serves as an abutment for the plate T. Only the plate S is directly connected to the shaft D as by means of a key V, and the plate T is secured to the plate S by means of bolts W upon which are disposed spacers in the form of sleeves X to prevent distortion of the outer extremities of the plates when the bolts W are threaded tightly into position.

Arranged on diametrically opposite sides of the plates S and T and mounted pivotally on two of the bolts W are a pair of centrifugal weights Y which are provided at one end with suitable apertures Z to receive the spacers X.

The weights Y have lateral arms b located adjacent the end of the weights wherein the apertures Z are formed. In each arm b is disposed a pin c to engage slots d in a circular plate e arranged rotatably upon the hub U of the plate S and between the weights Y.

Secured to one side of the plate e is a pin f which serves as an anchor for one end of a spring g adapted to resist the centrifugal movement of the weights Y. The opposite end of the spring g is seated against a spring seat h which extends into a groove i in the plate e and wherein the spring g is also arranged.

The spring seat h has an integral threaded stem k which extends through an arcuate slot o in the plate T, and on the stem k is threaded a nut p whereby the spring seat h may be clamped fixedly to the plate T. The slot o may be of suitable extent so that by shifting the spring seat h from one position to another along the length of the slot the tension of the spring g may be varied to resist the outward movement of the weights Y.

Arranged between the contact K and the shaft D is a lever q having a bore r near one end thereof to receive a pivot pin s which also extends through lugs t on the base B. The aperture r is located near the lowermost end of the lever q, and at the opposite end of the lever is a weight u which normally tends to hold the lever q in an unbalanced position.

The lever q carries an integral stop v which is adapted to engage a shoulder w on the base B when the lever q is held free from the contact K. The stop v and the weight u of the lever lie in different longitudinal planes so that when the lever is in the raised position illustrated in Figure 2, said lever will incline in the direction of the shaft D.

The following is a brief description of the op-

eration of the invention: During the time the engine A is operating at normal speeds the pressure of the spring g will maintain the weights Y in substantially the retracted position illustrated in Figure 2. If, during the course of its operation the speed of the engine should exceed that which it is desired to maintain, the free ends of the weights Y will move outwardly in the direction of the lever q.

10 When the engine, and therefore also the shaft D, attains that speed which may be considered excessive, the weights Y will move outwardly until they strike the weighted portion u of the lever q. In this way the lever q will be tilted 15 about the pivot s and the weighted portion u will cause the lever q to drop on the contact K. This will have the effect of grounding the magneto C so that the fuel charges in the cylinders

A will not be ignited. The engine will then come to a state of rest and may not be again started until the lever q has been removed from the contact K.

I claim:

A tripping device, comprising a rotatable bearing member, diametrically opposed centrifugally actuated weights pivoted on the bearing member, a circular plate in the bearing lying between the weights and being rotatable about the axis of said bearing, arms on the weights pivotally engaging the plate to actuate the plate relatively to the bearing, and springs within the plate and acting against the plate and the bearing to resist the centrifugal movement of the weights.
